EDWARD T. REDDING AND LEONARD W. CROSS, OF SWISSVALE, PENNSYLVANIA,
ASSIGNORS TO CONSOLIDATED EXPANDED METAL COMPANIES, A CORPORATION
OF PENNSYLVANIA.

APPARATUS FOR THE PRODUCTION OF EXPANDED METAL.

Application filed June 27, 1922. Serial No. 571,227.

To all whom it may concern:

Be it known that we, EDWARD T. REDDING, a citizen of the United States, and LEONARD W. CROSS, a citizen of Great Britain, both residing at Swissvale, in the county of Allegheny and State of Pennsylvania, have invented certain new and useful Improvements in Apparatus for the Production of Expanded Metal, of which the following is a specification.

Our invention relates to the production of expanded metal fabric, and more especially to apparatus for this purpose. Our invention permits and facilitates production of the fabric by a novel and highly advantageous method or process, which may be briefly explained as follows:

Metal fabric is ordinarily made according to two processes, one the "Golding," which is suitable for heavy stock and in which the diamonds are sheared from the blank by reciprocating die members, and the other the "deployed" method, suitable for lighter gauge stock such as used, for example, for metal lath and the other like meshes, some of which may be of material of heavier weight than ordinarily employed in lath. In this last process the blank is slit in a manner well understood and the metal is expanded by grasping the edges of the slit sheet and pulling them apart, so that the metal is deployed to produce the diamonds, the stretching of the strands being slight as compared with the stretching incident to the Golding process.

The novel process to which we have above referred differs from this old deploying one in that the various portions of the sheet separated by the slits are displaced transversely out of the original plane of the sheet as a whole to expand it and open up its mesh, instead of being simply tilted in the original plane of the sheet by a direct pull on the opposite edges in that plane. Aside from any differences in the final product of these two methods, that of deploying by transverse displacement affords

various practical advantages, such as greater rapidity and reduced cost of manufacture; reduction in floor space required; and continuous production of the expanded product in practically any width desired.

How these and other advantages can best be secured will appear from our description hereinafter of the preferred form of apparatus embodying our present invention in connection with the production of expanded metal fabric therewith by our method of transverse deploying.

In the drawings, Fig. 1 is a plan view of a portion of a longitudinally slit sheet metal blank resulting from the preliminary operations, and adapted for deploying by the transverse method; Fig. 2 is an end view of the blank; Fig. 3 is a view of the partially expanded blank looking edgewise at the unexpanded portion, illustrating the preferred mode of deploying in our apparatus; Fig. 4 is a side view of the fully expanded product, with a portion broken out; and Fig. 5 is an end view of such product; Fig. 6 shows a longitudinal vertical section through our preferred apparatus or machine, illustrating the various operations therein; Fig. 7 is mainly an end view, from the right of Fig. 6, showing certain parts in section as indicated by the line 7-7 in Fig. 6; Figs. 8 and 9 show transverse sections through the apparatus, taken as indicated by the lines 8-8 and 9-9 in Figs. 6 and 10 respectively; Fig. 10 is a side elevation of the apparatus, on a smaller scale; and Fig. 11 is a fragmentary plan view of the left-hand portion of the apparatus as shown in Fig. 10, on a larger scale.

In the production of expanded metal fabric with our apparatus by the transverse deploying method, we prepare a slotted blank A by passing a blank sheet through slitting rolls of ordinary general construction and operation (such as the rolls B, B shown at the extreme left of Fig. 6 and in Fig. 11). Preferably, the rolls employed for this purpose are designed to slit the blank with

longitudinal groups of slits 7 (two such groups being shown in Fig. 1) separated by an intermediate unslit longitudinal selvage portion 8, besides leaving it with unslit selvage portions 9, 10 along the edges. The slits of each group 7 are staggered in the usual manner, as shown.

Instead of further upsetting the slit portions of the blank A (as heretofore customary), we preferably pass it through flattening rolls (such as the rolls C, C shown near the left of Fig. 6 and in Fig. 11) to take out the slight upsetting of the strands incident to the slitting operation; for we find that this gives a greatly improved product, retaining maximum strength at the bridges connecting the strands.

From the flattening rolls C, C, the slit blank A passes to the deploying mechanism 20 of our apparatus (comprehensively indicated at D in Figs. 6 and 10), where it is deployed by transverse displacement, about as indicated in full lines in Fig. 3. As there shown, the extreme end portions of the selvages 9 and 10 have been brought down to a point such that the diamonds *a* at such end of the blank have been fully deployed or expanded, such expansion being progressively less full or complete toward the right. Successive lengths of the slit portions are progressively brought down in this manner, as indicated diagrammatically in the dotted lines in Fig. 3. Where the blank is composed of such stock that the selvage will not accommodate itself to the slight foreshortening of the sheets which takes place under the expanding process, such selvage can be crimped slightly, as indicated in exaggerated form at 11 in Fig. 3. The progressive displacement of the metal lends itself very well to the crimping operation as it will be apparent that it is only as diamonds are fully deployed that crimping may be necessary. This crimping, it will be understood, will only be slight at most as the amount of foreshortening is relatively small.

By deploying the metal downward at both sides of the intermediate selvage portion 8 in Fig. 1, the fully expanded sheet will ultimately be brought into an inverted V-shape (when looked at end-on), with the selvage 8 extending approximately parallel to the selvages 9 and 10, and the expanded portions 12 and 13 (which will ultimately constitute separate sheets) sloping off at an angle to one another. See Figs. 4 and 5. The selvages 9 and 10 may occupy exactly their original relative positions, without ever being moved apart at all.

Ultimately, the selvage portion 8, which is preferably of double width, is slit, leaving two separate sheets with margins of the desired width.

With this general explanation of the procedure, the specific details and operation of

the machine illustrated in Figs. 6 to 11 will be readily understood. Figs. 6 and 7 illustrate this most fully and comprehensively.

The blank A first passes through the slitting rolls B, B, which cut the groups of 70 slits 7, and then through the flattening rolls C, C, which take out the upsetting incident to the slitting,—as already described. If desired, the flattening rolls C, C may also have middle portions shaped to crimp the 75 inner marginal portion or middle selvage 8 (see Figs. 6 and 8). The rolls B, B and C, C act to pull the slit blank A forward, and thus also "feed" and advance it to the rest of the machine, including the expanding or 80 deploying mechanism D.

As the slit blank A enters the mechanism D from the rolls B, B and C, C the middle selvage or marginal portion 8 rides on to and along supporting means such as a bar 19, 85 which serves to sustain the pull of the deploying means necessary to draw transversely corresponding portions of the sheet at either side of said selvage down out of the original plane of the sheet, so as to deploy 90 it and open up its mesh. (In reference to the sheet as a whole, of course, the pull at either side of the selvage 8 is really and ultimately sustained by the deploying means pulling on the sheet at the other side,—the 95 support 19 in this aspect serving as a mere guide to change the direction of pull). As shown, the deploying means comprise interrupted guides formed by suitable plates 20, 21, 22, 23, etc., together with pairs of 100 substantially horizontal overhung rolls 31, 32, 33, etc., mounted and arranged in the intervals, and serving to draw the portions of the sheet to either side of the selvage 8 downward along the guides. As the selvage 8 105 rides on the support 19, the portions of the advancing sheet to either side thereof pass under the curved upper guide plates 20, 20, which deflect and direct these slit portions downward to the first pair of rolls 31, 31,— 110 whence they pass to the next pair of rolls, and so on. Owing to the downward inclination or divergence of the guides relatively to the guide support 19 and the original 115 plane of the sheet, the selvage 8 and the portions of the sheet acted on by the guides and rolls are advanced in diverging planes, and the latter are thus progressively drawn farther and farther out of their original plane, and the sheet thus progressively 120 deployed and expanded.

As shown in Fig. 7, especially, the guides 20, 21, 22, 23, etc., not only diverge (downward) from the supporting guide 19 in reference to the original plane of the sheet, 125 but also diverge crosswise of the sheet, to either side from positions closely adjacent said guide 19 and the selvage portion 8 supported thereby. Likewise, the successive pairs of rolls 31, 32, 33, etc., along the path 130

of the advancing sheet are not only located at greater and greater distances down from the guide 19 and the original plane of the sheet, but also terminated at greater and greater distances to either side of guide 19 and selvage 8, in correspondence with the positions of the immediately adjacent corners of the proceeding and succeeding guide plates 20, 21, 22, 23, 24, etc. In every case, the upper roll of a pair engages the metal between slits at the lower edge of the sloping expanded portion (12 or 13) of the sheet, while the transversely corresponding unexpanded portion of the sheet extends horizontally outward between the rolls. In the onward progress of the sheet, therefore, portions farther and farther from the selvage 8 (and hence nearer and nearer the selvages 9 and 10) loose the shelter of guide plates 20 and rolls, — so to speak, — and are drawn out of their original plane and expanded. In other words, various portions across the width of the sheet (and of each ultimate sheet 12, 13) are progressively and successively drawn and deployed farther and farther out of their original plane.

The crimping of the edge selvages or marginal portions 9, 10 may be done by rolls 40, and the inner margin or selvage 8 may be split by the cutters 41, 41. These rolls 40 and 41 serve to pull the sheet or blank through the machine, as well as the rolls B, C, 31, 32, 33, etc.

The various guide plates and rolls may all be suitably supported by a strong framework 42, 42. As shown in Fig. 9, the various pairs of rolls have intermeshing gears 43, and idlers 44 are also provided, so that all may be driven from any suitable source of power, as by means of a pulley 45 and gears 46, 47 of which the latter is mounted directly on the shaft of one of the rolls 35. The cutters 41, 41 may conveniently be driven from the rolls 40, 40, as by means of chain belts 48. Obviously, the production of expanded metal fabric in this apparatus is progressive and continuous, and the unbroken length in which the fabric can be produced is limited only by the length of plain sheet fed in.

We claim:

1. Apparatus for the production of expanded sheet metal comprising means for progressively and successively drawing portions nearer and nearer an outer unslit margin of a slit sheet out of their original plane, to deploy the sheet and open up its mesh, and means for engaging the adjacent unslit margin and thereby sustaining the pull exerted in deploying the sheet.

2. Apparatus for the production of expanded sheet metal comprising guide means for loosely engaging and thereby sustaining a marginal portion of an advancing slit sheet, and pairs of revolving rolls arranged at successively greater distances from the

plane of said marginal portion for drawing the various portions across the width of the sheet farther and farther out of their original plane.

3. Apparatus for the production of expanded sheet metal comprising means for sustaining a marginal portion of an advancing slit sheet, interrupted guide means diverging from said sustaining means in reference to the original plane of the sheet, and pairs of revolving rolls arranged in their intervals for drawing the sheet along the guides to deploy it and open up its mesh.

4. Apparatus for the production of expanded sheet metal comprising means for sustaining a marginal portion of an advancing slit sheet, interrupted guide means diverging from said sustaining means both transversely of the sheet and in reference to its original plane, and pairs of revolving rolls arranged in intervals of said guide means.

5. Apparatus for the production of expanded sheet metal comprising means for slitting the sheet; means for crimping one marginal portion; means for progressively and successively drawing portions farther and farther away from such marginal one out of their original plane, to deploy the sheet and open up its mesh; and means for crimping the other marginal portion as the slit portions adjacent thereto are deployed.

6. Apparatus for the production of expanded sheet metal comprising means for supporting an intermediate portion of a slit sheet, and means for progressively and successively drawing portions further and further away from that supported as aforesaid downward to either side of the support to open up its mesh.

7. Apparatus for the production of expanded sheet metal comprising guide means for supporting an intermediate portion of an advancing slit sheet, and means diverging outward from one another and downward to either side from said supporting means for progressively and successively drawing portions of the sheet further and further to either side of the supported portion down out of their original plane, so as to deploy the sheet and open up its mesh.

8. Apparatus for the production of expanded sheet metal comprising guide means for supporting an intermediate portion of an advancing slit sheet, interrupted guide means diverging downward and to either side from that first mentioned, and pairs of revolving rolls arranged in intervals of said guide means for successively and progressively drawing portions of the sheet farther and farther to either side of the supported portion downward out of their original plane, so as to deploy the sheet and open up its mesh.

9. Apparatus for the production of ex-

paned sheet metal comprising means for supporting an intermediate portion of an advancing slit sheet; and overhung rolls for progressively and successively drawing portions farther and farther away from the supported portion out of their original plane, said rolls being arranged along the path of the advancing sheet, in pairs, at

successively greater distances from the plane of the supported portion of the sheet and ¹⁰ with their free ends at successively greater distances to either side of such portion.

In testimony whereof, we have hereunto signed our names.

EDWARD T. REDDING.
LEONARD W. CROSS.
